(57) CLAIM

The ornamental design for a pair of handbag struts, as shown and described.

DESCRIPTION

FIG. 1 is a top perspective view of pair of handbag struts showing my new design;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is left side view thereof with the opposite side being identical in appearance;

FIG. 8 is an environmental bottom view attached to purse thereof; and,

FIG. 9 is an environmental bottom perspective view attached to purse thereof.

The broken lines showing a handbag are for the purposes of illustrating environment and forms no part of the claimed design.
